LUBRICANT-FEEDING APPARATUS FOR INTERNAL COMBUSTION ENGINES

Johan Ferdinand Julius Clementson, Malmo, Sweden, assignor to C. & S. Clementson, Malmo-Limhamn, Sweden, a firm composed of Messrs. Carl Clementson and Sven Clementson

Application March 30, 1938, Serial No. 199,013
In Sweden November 5, 1937

4 Claims. (Cl. 123—196)

The present invention relates to apparatus for admission of a certain predetermined quantity of lubricant oil to the valves, cylinders and pistons in internal combustion engines when starting the same.

In order completely to eliminate the wear due to corrosion in internal combustion engines, it has been found necessary to introduce into the same a relatively large quantity of a corrosion opposing lubricant oil when starting the engine in cold condition, whereas the normal quantity of such corrosion opposing oil usually admixed with the fuel is sufficient to prevent corrosion wear at the continued running of the engine when it has reached the normal running temperature.

The invention provides for an automatically acting apparatus for such purpose, and its main feature is a smaller measuring container the volume of which corresponds to the quantity of lubricant oil intended to be fed into the engine at the start. This measuring container stands in communication with a supply container from which the lubricant oil is fed into the former by means of hydrostatic pressure, or otherwise, and with the intake manifold of the engine, and the measuring container is provided with valve means for control of the oil inlet from the supply container and of the oil outlet to the engine, the control being effected under influence from a force of known strength arising, or being liberated, when starting the engine in cold condition and acting in such a manner that the inlet to the measuring container is closed substantially simultaneously with the opening of the outlet from the same to the engine. The said force occurring when starting the engine may be generated, for instance, by electric current when closing the engine circuits (such as for ignition or self-starting, etc.), the ordinary engine lubricating oil pressure, the vacuum within the engine suction pipings or the increased pressure within the exhaust pipings, compressed air pressure, when using compressed air for self-starting purposes, or any other force or power whatever generated, or liberated, when starting the engine, such force acting in a suitable manner upon means for control of the valve means combined with the measuring container. The apparatus may also be provided with suitable means for eliminating the influence of the said force upon the valve means as soon as the engine has reached a certain running temperature, so that no admission of lubricant oil from the measuring container will take place thereafter.

An embodiment of the invention is illustrated in the accompanying diagrammatical drawing which shows the different parts of construction seen in vertical section, when supposing that a closing of the electric circuit through the self-starter also closes the circuit through an electrically actuated control means for the valve means referred to.

In the drawing, 1 is the supply container for the lubricant oil which preferably consists of a corrosion opposing oil of a known kind, and a certain quantity of which is also admixed with the fuel oil in the proportion ordinarily employed. By means of hydrostatic pressure, or otherwise, the oil is fed from the container 1 through a pipe 2 into the smaller measuring container 4 which at its upper end is provided with an inlet 3 connected with the pipe 2, and at its lower end with an outlet 15 communicating with a pipe 16 connected with the intake manifold 17 of the engine closely adjacent to the engine cylinders.

The measuring container encloses a valve means consisting of a spindle 12 extending vertically through the said container and provided at its upper end with a valve plate 13 adapted for closing the inlet from the supply container 1, whereas the lower end of the spindle is provided with a valve plate 14 adapted for closing the outlet to the intake manifold 17 of the engine. The measuring container is also provided with an air vent 5.

The valve spindle 12 is kept in its lowermost position by means of a tension spring 28, and in such position the valve plate 14 closes the outlet from the measuring container to the pipe 16, whereas the valve plate 13 leaves open the inlet from the supply container 1. The lowermost end of the spindle 12 is connected with a lever arm 11 by means of a cross pin extending through slots in the wall of the pipe 16, and the said lever arm is tiltably mounted in a bracket extending from the container 4, the free end of the lever arm being hingedly connected with the movable core 10 of a solenoid 9. The said solenoid is electrically connected with the metallic body of the engine over a thermostatically influenced switch 26—27, and the minus pole of the ordinary storage battery 6 is also connected with said body. The opposite terminal of the solenoid winding is connected with the ordinary circuit 8 of the engine in such a manner, that the solenoid is switched on to the storage battery simultaneously with other portions of the ordinary engine circuit (for ignition or self-starter, etc.). Hence, the solenoid and

the thermostatic switch are together coupled in parallel with the engine circuit 8.

The thermostatic switch may be of any suitable known type, and in the drawing it is supposed to include a flexible bellows 23 filled with an easily volatile liquid and counter-sunk within the cooling jacket of the cylinder head of the engine so as permanently to be subjected to the temperature at hand at this place. The free upper end of the bellows 23 supports a spindle 25 provided with a movable contact 26 of the switch, whereas the other contact 27 of the same is fixed and insulated from the cylinder block. On the other hand, the movable contact 26 is electrically connected with the metallic body of the engine.

The manner of action of the apparatus described is as follows:

When the engine is kept stopped and cold, 20 the valve spindle 12 is kept in its lower position by means of the spring 28, and the valve plate 14 closes the outlet 15 from the measuring container 4, whereas the valve plate 13 leaves open the inlet 3 to the said container. The 25 measuring container will then be filled by the oil admitted from the supply container 1 by the pipe 2, simultaneously as the air escapes through the vent 5. Hence, the measuring container 4 during normal conditions, i. e. when the apparatus 30 is out of action, is always kept filled with oil from the supply container.

When the engine is cold, the bellows 23 of the thermostatic switch is contracted and keeps the contacts 26, 27 pressed against each other. 35 When starting the engine, the circuit through the self-starter is closed by the manually operated switch means 7, and simultaneously the solenoid 9 coupled in parallel therewith is energized. Then the core 10 is attracted and lifts 40 the lever arm 11 which acts upon the spindle 12 of the valve means within the measuring container, so that the valve plate 13 closes the inlet 3 whereas the valve plate 14 opens the outlet 15. The oil accumulated within the measuring 45 container will then flow down through the pipe 16 into the intake manifold 17 of the engine, and from there it will be passed through the engine valves 18 together with the fuel and the combustion air entering the combustion chamber 50 19 in which the oil is deposited on the cylinder walls 20 and pistons 21. The admittance of oil from the supply container 1 to the measuring container 4 has been simultaneously interrupted, however, so that no new quantity of oil can pass 55 down into the latter as long as the outlet 15 therefrom is kept open. A cock valve 22 mounted in the outlet pipe 16 serves to control the rapidity of the discharge of oil from the measuring container.

When the temperature of the engine is increasing, the thermostat bellows 23 expands so that the contacts 26 and 27 are separated as soon as a certain temperature has been reached. Thereby the circuit through the solenoid 9 is interrupted, and the spring 28 returns the valve spindle 12 together with the lever arm 11 and the core 10 into their starting positions. Thereby the outlet 15 from the measuring container 4 is closed again, simultaneously as the inlet 3 to the same is re-opened, so that the measuring container will be re-filled from the supply container 1 through the pipe 2.

At the continued running of the engine, the quantity of corrosion opposing oil admixed with 75 the fuel will be sufficient completely or mainly

to prevent corrosion wear within the engine. As long as the engine is sufficiently hot and the contacts 26 and 27 are kept apart by the thermostat bellows 23, the circuit cannot be closed through the solenoid 9, even in case the engine is stopped for a short period and re-started again.

It ought to be evident that the invention is not limited to the embodiment thereof described in the foregoing and shown in the annexed drawing, 10 as such embodiment forms an example only chosen for the sake of explanation of the invention, and it may be varied in many respects within the scope of the same. The force generated, or liberated, when starting the engine in cold 15 condition and serving to actuate the valve means in connection with the measuring container may emanate from the lubricant oil pressure in the ordinary lubricating system of the engine instead of being electric current passed through the engine circuit, and such oil pressure may for instance be adapted by means of a piston reciprocable within a cylinder directly to act upon the lever arm 11 or the valve spindle 12. Any other force whatever arising in connection with 20 the starting of the engine may likewise be employed for the same purpose, such as for instance the vacuum within the intake manifold of the engine, the pressure within the exhaust pipe, or a dynamic power generated directly by the engine. In connection herewith, the thermostatic device adapted to interrupt the transmission of this force, or power, to the valve means in connection with the measuring container ought naturally also to be constructed in a suitable manner for serving its purpose. When the valve means are pressure controlled, the thermostatic device may for instance act directly on a valve means adapted to interrupt the admission of the actuating pressure to the control mechanism. 30 The construction of the thermostatic device is also rather irrelevant, and it may be of the bimetallic type, for instance, or consist of any other suitable thermostatically acting device whatever. Many other constructional details may also be 35 varied in relation to those shown in the drawing, within the scope of the invention.

What I claim and desire to secure by Letters Patent is:

1. In a lubricant-feeding apparatus for internal combustion engines and of the character described, a supply container for the lubricant oil, a measuring container having an inlet means in communication with the supply container and an outlet means in communication with the intake suction pipings of the engine, valve means provided in connection with the measuring container and adapted to control the inlet thereto from the supply container and the outlet therefrom to the engine so that an opening of the outlet from the measuring chamber is performed substantially simultaneously with a closing of the inlet from the supply container, an actuating device adapted to be controlled by a force, or power, generated, or liberated, in connection with the starting of the engine, and thereby to shift the positions of the valve means, and a thermostatic means standing under influence of the engine temperature and adapted to interrupt the transmission of the controlling force, or power, to the valve means shifting device when the engine has reached a desired running temperature. 55

2. In a lubricant-feeding apparatus according to claim 1, the additional feature that a control valve means is interposed in the piping connect- 75

ing the measuring container with the engine and adapted to control the rate of flow through said piping.

5. In a lubricant-feeding apparatus for internal combustion engines and of the character described, a supply container for the lubricant oil, a measuring container having an inlet means in communication with the supply container and an outlet means in communication with the intake suction pipings of the engine, valve means provided in connection with the measuring container and adapted to control the inlet thereto from the supply container and the outlet therefrom to the engine so that an opening of the outlet from the 10
15 measuring container is performed substantially

simultaneously with a closing of the inlet from the supply container, means for shifting the valve means into the position just mentioned, and thermostatically acting means standing under influence of the engine temperature and adapted 5 to reverse the positions of the valve means when said temperature has reached a predetermined running value.

4. In a lubricant-feeding apparatus according to claim 3, the additional feature that a control 10 valve means is interposed in the piping connecting the measuring container with the engine and adapted to control the rate of flow through said piping.

JOHAN FERDINAND JULIUS CLEMENTSON. 15
